UNITED STATES PATENT OFFICE.

BERTRAM E. WOOD, OF COLORADO SPRINGS, COLORADO.

MAGNETIC SEPARATOR.

971,163.

Specification of Letters Patent. Patented Sept. 27, 1910.

Application filed December 27, 1909. Serial No. 535,104.

To all whom it may concern:

Be it known that I, BERTRAM E. Wood, citizen of the United States, residing at Colorado Springs, in the county of El Paso and State of Colorado, have invented new and useful Improvements in Magnetic Separators, of which the following is a specification.

My invention pertains to magnetic separators; and it contemplates the provision of a simple and efficient magnetic separator designed more especially for removing black or magnetic sand from gravel or other sand in dry placering, with a view of preventing the black sand, which is of approximately the same weight as the gold, from gathering in and clogging up the riffles and interfering with the collection of values.

The novelty, utility and practical advantages of the invention will be fully understood from the following description and claim when the same are read in connection with the drawings, accompanying and forming part of this specification, in which:

Figure 1 is a side elevation of a magnetic separator constructed in accordance with my invention. Fig. 2 is a view taken at a right angle to Fig. 1 and in a line in front of the endless non-magnetic apron. Fig. 3 is a transverse section taken in the plane indicated by the line 3—3 of Fig. 2, and showing the preferred construction of magnet employed.

Similar letters designate corresponding parts in all of the views of the drawings, referring to which:

A A are uprights comprised in a suitably supported frame work, and B, C and D are cross-bars extending between and fixed to the uprights; the said uprights and cross-bars being preferably of wood.

In suitable bearings on the uprights A are journaled lower and upper transverse shafts E and F, equipped with rolls G, and around the said rolls G is passed a non-magnetic endless apron H, of a material suitable to the purpose of said apron. It will also be noticed that I show the upper shaft as having fixed thereon a band pulley I for receiving a belt from a suitable motor (not shown), and through the medium of which rotary motion may be transmitted to the shaft F and the roll G that is fixed thereon in order to drive the apron H in the direction indicated by arrow.

Arranged between the front stretch of the

apron H and the frame work, and resting on the lower and upper cross-bars B and D, and against the intermediate cross-bar C and suitably fixed with respect to the frame work, is the magnet J. This magnet is preferably of the type and construction illustrated—that is to say, it comprises the body a, wound with coils b, designed to be connected with a source of electric energy (not shown). The lower portion of the body a is straight and vertically disposed, and the upper portion thereof is curved rearwardly and toward the inclined frame work as illustrated. It will also be understood by comparison of Figs. 1, 2 and 3 that the body a is recessed, as indicated by c, to receive the coils b, which extend practically throughout the length of said body, and that the upper curved portion of the body has its face recessed to receive anti-friction rollers or wheels d. These wheels or rollers d in combination with wheels or rollers e disposed at opposite sides of the magnet body a are designed to support the apron H in its passage over the upper curved portion of the magnet body and in that way prevent undue wear of the apron and at the same time adapt the apron to be driven with the expenditure of little power.

Located at about the distance illustrated from the front stretch of the apron H is a wall K designed to serve in combination with said stretch to form a vertically disposed conduit, and above the said conduit is disposed and suitably supported a hopper L or other suitable means for feeding commingled sand and gravel to the said conduit. It will also be understood by reference to Fig. 1, that I provide a conduit M for receiving black or magnetic sand from the apron as the same passes over the upper roll G, and that I further provide a guide P for receiving the gravel and values from the lower end of the conduit formed between the wall K and the front stretch of the apron H.

In the practical use of my novel separator the apron H is driven in the direction indicated by arrow, and the sand and gravel is fed in a continuous stream through the vertical conduit in front of the apron, whereupon the magnet will operate to cause the black or magnetic sand to approach and adhere to the front stretch of the apron. Such sand will be held to the apron by the influence of the magnet until the apron approaches and passes over the upper roll G,

whereupon the said sand will be discharged into the conduit M.

It will be gathered from the foregoing that in proportion to its size and cost my 5 novel separator is possessed of large capacity; and it will also be appreciated that the separator is simple, compact and inexpensive, and is well adapted to withstand the usage to which magnetic separators are 10 ordinarily subjected.

While I have shown and described one form of my invention, it is to be understood that I am not limited to the details or the 15 form or relative arrangement of parts disclosed, but that modifications may be made therein without departing from the spirit thereof.

Having described my invention, what I claim and desire to secure by Letters-Pat- 20 ent, is:

In a magnetic separator, the combination of a suitably supported inclined frame having lower and upper cross-bars, an electro- 25 magnet having a body made up of a lower upright portion that bears on the lower cross-

bar and an upper rearwardly curved portion that rests at its end on the upper cross-bar; said electro-magnet also having recesses in the faces of its upright and rearwardly curved portions and further having coils in 30 said recesses and anti-friction wheels in the face of the upper rearwardly curved portion and also in the curved portions of the coils, a suitably supported roll disposed in rear of the upper rearwardly curved portion 35 of the magnet body, a suitably supported roll disposed below the lower end of the magnet body, an endless non-magnetic apron arranged on the rolls and in front and rear of the electro-magnet, and an upright wall 40 spaced from the front stretch of the apron and forming with the same an upright conduit.

In testimony whereof I have hereunto set my hand in presence of two subscribing wit- 45 nesses.

BERTRAM E. WOOD.
